CLAIM

The ornamental design for audio video shelving unit, as shown and described.

DESCRIPTION

FIG. 1 is a top perspective view of the subject audio video shelving unit;

FIG. 2 is a front plan view thereof;

FIG. 3 is a rear view thereof;

FIG. 4 right side view thereof (the left side being a mirror image of the right side view);

FIG. 5 is a top plan view thereof;

FIG. 6 is a front perspective view of a second embodiment of the subject audio video shelving unit; and,

FIG. 7 is a top plan view (FIGS. 2-4 being the same as views shown in the first embodiment.)
